DOLEN D. DYER, OF BRANDYWINE, WEST VIRGINIA

AUTOMOBILE CARD CASE

Application filed September 8, 1930. Serial No. 430,577.

This invention relates to a case for holding a registration card or the like to a part of a motor vehicle, the general object of the invention being to provide the case with a base part which is attached to a part of the vehicle and a part hinged to the cover and having a transparent member, with means for holding a registration card or the like against the inner face of the member, where-
5 by the card is visible and is held in the case so that it is protected from dirt, dust, mois-
ture and the like.

This invention also consists in certain other features of construction and in the 15 combination and arrangement of the several parts, to be hereinafter fully described, illus-
trated in the accompanying drawing and specifically pointed out in the appended
claim.

20 In describing the invention in detail, reference will be had to the accompanying drawing wherein like characters denote like or corresponding parts throughout the several views, and in which:—

25 Figure 1 is a front view of the device.

Figure 2 is a section on line 2—2 of Fig-
ure 1.

Figure 3 is a sectional detail view showing the latch means for holding the cover in 30 closed position.

Figure 4 is a section on line 4—4 of Fig-
ure 3.

In these views, the numeral 1 indicates the base of the device which is adapted to be connected with a part of the vehicle by the bolts 2, this base having the side flanges 3 so that its major portion will be spaced from the part to which it is attached. The cover 4 is hinged to the base, as shown at 5, and said 35 cover part is preferably composed of side and end portions which are of substantially V shape in cross section, with the outer portions 6 adapted to rest against portions of the base 1 so as to form a tight joint when the cover 40 is closed. The cover carries a transparent member 7 and the registration card 8 rests against the inner face of the transparent member and said member and the card are re-
movably held in place by the clips 9 which 45 are pivoted to the cover portion. Leaf
50

springs 10 are fastened to the base 1 and press against the card when the cover is closed so as to hold the card against the transparent member and said member against the inner flanges of the cover 4.

55 A spring strip 11 is fastened to a vertical wall of the base at that side which is opposite the hinge and a depending spring strip 12 is fastened to the cover and is engaged by a projection 11' on the strip 11 when the cover is closed so that these parts 11 and 12 form latch means for the cover. The cover is formed with a keyhole 13 so that a key 14 can be passed therethrough and when turned, will engage the strip 11 so as to push it out of 60 engagement with the strip 12, thus permitting the cover to be opened.

65 From the foregoing it will be seen that I have provided a casing having a hinged cover formed with a transparent portion so that a 70 registration card or the like will be visible through the transparent member when placed in the device. By locking the cover in closed position, the registration card cannot be stolen without damage to the device 75 and the card is kept in good condition by the device.

75 It is thought from the foregoing descrip-
tion that the advantages and novel features of the invention will be readily apparent.

80 It is to be understood that changes may be made in the construction and in the combination and arrangement of the several parts, provided that such changes fall within the scope of the appended claim.

85 What I claim is:—

A device of the class described comprising a base portion, a cover portion hingedly connected therewith, said portion having an opening therein, a transparent member 90 covering the opening, a card resting against the inner face of the transparent member, pivoted clips for holding the card and transparent member in place, springs carried by the base portion and pressing against the 95 card and means for locking the cover in closed position.

In testimony whereof I affix my signature.

DOLEN D. DYER. 100
